UNITED STATES PATENT OFFICE

167,776

TRAVEL IRON

Richard O. Spencer, Santa Monica, Calif., and
Bradford R. Voight, Milford, Conn., assignors
to General Electric Company, a corporation of
New York

Application May 3, 1951, Serial No. 15,049

Term of patent 14 years

(Cl. D49—6)

To all whom it may concern:

Be it known that we, Richard O. Spencer and Bradford R. Voight, citizens of the United States, residing respectively at Santa Monica, in the county of Los Angeles, State of California, and at Milford, in the county of New Haven, State of Connecticut, have invented a new, original, and ornamental Design for a Travel Iron, of which the following is a specification, reference being made to the accompanying drawing, forming part thereof.

In the drawing:

Fig. 1 is a perspective view, from the front and side, of a travel iron, showing our new design; and

Fig. 2 is a perspective view, from the rear and side thereof. The design is symmetrical, and the hidden side has the same appearance as the one shown.

We claim:

The ornamental design for a travel iron, substantially as shown.

RICHARD O. SPENCER.
BRADFORD R. VOIGHT.
